UTILIZATION OF PETROLEUM REFINERY
GAS

Eric B. Hjerpe, Port Arthur, Tex. and William A. Gruse, Wilkinsburg, Pa., assignors to Gulf Oil Corporation, Pittsburgh, Pa., a corporation of Pennsylvania

Application May 7, 1936, Serial No. 78,480

1 Claim. (Cl. 260—683)

This application is in part a continuation of our application Serial No. 613,774, filed May 26, 1932, now U. S. Patent No. 2,099,480.

The invention covered by this continuation-in-part application relates to the utilization of petroleum refinery gas, and comprises a continuous process wherein refinery gas containing methane, ethylene, ethane, propylene, propane, butylene, butane, pentanes and higher boiling constituents, is stripped of its contained gasoline vapors (pentanes and higher boiling components); the residue is next stripped of methane for deposition as desired; and the residue from the last mentioned separation is further subjected to successive fractionation for isolation of cuts containing individual olefins such as ethylene, propylene and butylene; the charging stock for a polymerization or gas conversion operation conducted for the purpose of producing motor fuel.

More specifically, this invention provides a continuous process wherein uncondensed gas from the customary water-cooled condensers of petroleum cracking stills and/or coke stills and/or steam stills (said gas comprising methane, ethylene, ethane, propylene, propane, butylene, butane and higher boiling components) is subjected to compression and/or absorption steps to liquefy and thereby separate and remove higher boiling constituents, leaving a residue of stripped refinery gas. This stripped refinery gas is chilled to a temperature sufficient to liquefy all components higher boiling than methane and is introduced into a tower and the methane fractionated out, the necessary chilling of the gas being effected by expanding it through an expansion valve after compressing it to the necessary degree and cooling it with water. The liquid residue from the last mentioned tower is expanded into the second tower and the ethylene and ethane are similarly fractionated out; the liquid residue of the last mentioned separation, now freed of ethylene, ethane and methane, is expanded into a fractionating tower and the propylene and propane are fractionated out from residual butylene and butane.

In particular, our invention relates to a method of fractionating gases of the character indicated, in which the gases after fractionation thereof, are passed through a series of fractionating steps in which constituents or fractions of successively higher boiling points are removed, residual liquid from any one of the aforesaid towers being employed to assist in the fractionation and separation taking place in a preceding tower.

In order that our invention may be clearly set

forth and understood, we now describe, with reference to the drawing accompanying and forming a part of this specification, a preferred manner in which our invention may be practiced and employed.

In the drawing the single figure is a more or less diagrammatic view of apparatus for carrying out our invention arranged primarily as a flow sheet.

Referring to the drawing, the numeral 1 indicates a stream of charging stock to a conventional cracking still comprising a cracking coil 2, separating and dephlegmating tower 3, condenser 4, and separator 5. These elements do not constitute a portion of this invention but are included for clarity of presentation. After condensation of cracked distillate in the condenser 4 the distillate is separated from accompanying uncondensed gas in separator 5. This gas, conducted away through line 6, is raw material used in the process which constitutes our invention. Other raw material for our process is the corresponding uncondensed gas from petroleum coking stills, lubricating stills, and steam stills. Any one of these gases alone or any mixture of them is acceptable raw material and this raw material will hereinafter be referred to as still gas, or petroleum refinery gas.

As a preliminary step, the gas is first stripped of pentanes and all higher boiling constituents. Some butane and butylene may be removed at this point, if it is desired to retain this material as such in the cracked gasoline. This separation may be effected in various ways and we have found compression and absorption methods very satisfactory, with subsequent controlled fractionation of the absorbed material. Absorption is most effective when we maintain a super-atmospheric pressure of the order of 250 pounds or 300 pounds in the absorber. The compression can be effected in two stages as shown in the drawing, with recooling of the gas after each compression stage. This compression and subsequent cooling will liquefy some of the higher boiling constituents of the gas and so a separator is placed in the line which conducts the cooled gas from one compression stage to another compressor. Liquefied material removed from this separator is termed compression gasoline. The drawing depicts two-stage compression with compressors 7 and 10, followed by recooling in coolers 8 and 11 respectively, and removal of compression gasoline at separator 9, positioned immediately before the second compressor. The compression gasoline is conducted away from separator 9 through line 13. After compression to

the desired degree, and subsequent recooling as described, the gas is introduced into an absorber 12 where it flows countercurrent to and in open contact with a stream of absorbent oil introduced 5 thereto through line 14. The absorbent oil absorbs practically all higher boiling normally liquid constituents of the gas, and the remainder of the gas, which we shall term stripped refinery gas, leaves the absorber through line 15. The 10 presence of plates in the absorber adds greatly to its effectiveness. The absorbent oil, rich with dissolved constituents of the gas, leaves the bottom of absorber 12 through line 16 and is introduced through line 18 into a tower 19 where the 15 absorbed constituents of the gas are distilled off and fractionated. Tower 19 is preferably operated under a superatmospheric pressure and should its pressure not be sufficiently below that of the absorber to cause the necessary flow 20 through lines 16 and 18, a pump 17 can be inserted in the line to effect the transfer of the liquid. Heat for distilling the absorbed constituents of the gas out of the absorbent oil in tower 19 is provided by a closed steam coil or equivalent 25 heating means in the lower portion of the tower. The upper portion of tower 19 is designed to effect clean fractionation of the absorbed material from the absorbent and the so-fractionated vapors from tower 19 pass to, and are condensed 30 by, condenser 20. The effluent of the condenser passes to gas separator 21 where any unliquefied components of the gas are separated from the liquefied components. The condenser 20 and gas separator 21 are maintained under the same 35 pressure and the pressure and temperature of the condenser are chosen to assure liquefaction of normally liquid constituents without liquefaction of normally gaseous constituents, for example, propane and propylene. Any higher boiling 40 fractions of the refinery gas which are liquefied in condenser 20 and separated from accompanying gas in separator 21 are conducted away through line 22. That portion of the petroleum 45 refinery gas which passes through condenser 20 without being liquefied therein passed out of the top of gas separator 21 through line 23. This line joins line 15, previously described, and the combined stream is termed stripped refinery gas. This stripped refinery gas contains butylene and 50 butane and all of the lower boiling constituents of the petroleum refinery gas. The relative proportions of the various constituents vary widely according to the kind of oil from which it originates, the kind of still in which it is produced, 55 the temperature, pressure, and other conditions attending its creation, and the condensation of accompanying vapors in the still condenser (condenser 4 or its equivalent). One typical analysis of the stripped refinery gas—insofar as any 60 analysis could be termed typical—was the following, observed in operation of the process herein described and claimed:

	Per cent
Methane	45
Ethylene	5
Ethane	20
Propylene	8
Propane	15
Butylene	3
Butane	4

Our next step is to fractionate out the methane. We do this by introducing the stripped refinery gas at a sufficiently low temperature into a fractionating tower and the low temperature is obtained by self-cooling incident to expansion

through an expansion valve or work engine. Further details follow. The stripped refinery gas in line 15 is compressed to whatever degree is necessary to effect that cooling at the expansion valve which is requisite for liquefaction at 5 tower pressure of all constituents of the gas which boil at higher temperatures than methane. The tower pressure is advantageously chosen to permit further pressure drop in subsequent fractionating steps and yet maintain suitable working pressure at the last fractionating step. The methane is fractionated out in the tower 35 and in our practice of the invention we have found a pressure of 500 pounds per square inch above atmospheric, before expansion, to be suitable for a 15 gas such as the one which an analysis is shown above, and a pressure of seven atmospheres within the tower to be quite satisfactory. This pressure is generated by compressor 24 and the heat generated in compression is removed from the 20 gas by a cooler 25. The compressed and recooled gas is then in condition for chilling by expansion, for introduction into the tower at 33 and for fractionation therein. Expansion and consequent cooling is effected at expansion valve 31. Maintaining a pressure of seven atmospheres within this tower we take off the 45 per cent methane content of the gas with a tower head temperature of minus 140° C. and the remainder of the gas leaves the base of the tower in liquid form at 30 a temperature of minus 60° C. The fractionation in the tower is more easily controllable if we have a chilling means in the tower head and a warming means in the tower base. These are readily provided for by closed coils 27 and 32 in 35 the tower base and head, respectively, and bypass connections in the incoming gas line, to admit of circulating this gas therethrough in such quantity as is necessary to obtain the required control. Three valves 28 are shown for permitting the use of regulated amounts of the unexpanded gas for controlling the temperature of the tower base and similar by-pass connection and valves are provided to permit the use of regulated amounts of the expanded gas for controlling the temperature of the tower head. The by-pass connection and valves 28 have been illustrated in connection with coil 27, their similar arrangement in connection with head coil 32 has been omitted from the drawing for simplicity of 50 illustration. These same remarks apply as to the head coils in towers 40 and 75, each of which is provided with by-pass connections similar to coil 27, but which connections have been omitted from the drawing for simplicity of illustration. 55 Immediately before expanding the gas through expansion valve 31 we may pass it through a heat interchanger 30 wherein it is cooled by heat interchange with methane leaving tower 35 at very low temperature. The heat interchanger may be 60 superimposed upon tower 35 and communicate therewith through a pierced diaphragm 36. The methane finally flows away through line 37 for utilization.

The liquid residue leaves tower 35 through line 65 34 and comprises ethylene, ethane, propylene, propane, butylene and butane. This liquid is discharged into tower 40 at 42 for fractionation of ethylene and ethane from the propylene, propane, butylene, and butane. Tower 40 may be 70 provided with coils 38 and 39 for assisting in controlling the head and base temperatures thereof, and these coils are connected with line 34 in by-pass arrangement and sequence as already fully described in connection with coils 27 75

and 32. A pressure of six atmospheres is maintained in tower 40 and the ethylene and ethane leave the top of the tower through line C at a temperature of minus 50° C., while the propylene, propane, butylene, and butane leave the base of the tower through line 43 at a temperature of minus 15° C.

A mixture of propylene, propane, butylene, and butane is removed from the base of tower 40 through line 43 under a pressure of six atmospheres. This is conveyed through line 43 to tower 75, and is expanded at expansion valve 71 prior to its introduction thereinto at 14. Tower 75 is provided with base coil 72 and head coil 73 similar to coils 27 and 32 of tower 35 and completely described in that connection. The contents of line 43 or a portion of them may be by-passed through coil 72 for regulation of the temperature of the tower base, and all or a portion of them, after expansion through valve 71, may be by-passed through coil 73 for regulation of the tower head temperature. As previously stated the by-pass connections for coil 73 have been omitted from the drawing for purpose of simplification. We operate tower 75 at a pressure of five atmospheres and maintain therein a head temperature of 0° C. and a base temperature of plus 35° C. Thereby we effect fractionation of the incoming stream and take off from the tower head, through line 76, a mixture of propylene and propane, and from the tower base we take off a residue of butylene and butane through line D. The butylene-butane fraction is conducted away through line D for further utilization as desired.

Throughout the various fractionations in the process illustrated, we may improve the separation by discharging a portion of the more closely separated product of one tower back to the head of the previous tower, to constitute an open reflux stream therein. Thus, a portion of the liquid product removed from the tower 40 through the line 43 may be returned through a line 80 having a pump 81 and a valve 82 to the upper portion of the tower 35, to serve as a reflux and absorbing and concentrating medium. By means of the valve 82 and a further valve 83 located in the line 43, the proportions of the liquid withdrawn from the bottom of the tower 40 and returned to the tower 35 or delivered to the tower 75 respectively, may be suitably adjusted in the usual manner.

Similarly, a portion of the butane containing fraction removed from the bottom of the tower 75 through the line D, may be delivered to the tower 40 as reflux. For this purpose, we provide a line 85 having a valve 86 and a pump 87 and communicating at one end with the line D and terminating at the other end in the upper portion of the tower 40. An additional valve 88 may be provided in the line D which with the valve 86 may be employed for the purpose of regulating the proportion of the liquid returned as reflux to the tower 40 and such excess liquid as may be withdrawn through the line D.

Throughout the various steps of our process for utilizing petroleum refinery gas we can of course reduce the number of steps in fractionating out a cut containing any particular olefin when it does not disadvantageously affect the usefulness of adjacent fractions or where, under the particular circumstances, the adjacent fraction is not to be used. Likewise, where it does not affect the usefulness of adjacent fractions, we can fractionate to get the desired olefin as the principal

content of the fraction, accompanied only by minimal quantities of the components having adjacent boiling points.

It will be clearly seen from the foregoing description that in our process refinery gases which are to be separated into two fractions relatively high and relatively low respectively in a low-boiling and refractory constituent, such as ethane or ethylene, are introduced into a fractionating tower, to the upper portion of which is supplied as reflux a liquid free or substantially free of such constituent and comprising, for example, butane and butylene. The bottoms from this fractionating tower are then subjected to a second fractionation for the purpose of removing any constituents absorbed by the reflux and the bottoms from the second tower, thus stripped of said absorbed constituents, are returned at least in part to the first fractionating tower as a refluxing and absorbing medium, it being understood that the function of absorption is inherent in the action of a liquid reflux.

As a result of this absorbing and stripping action, the overhead from the second tower is substantially richer in high boiling and hence less refractory constituents, for example propylene and propane, than the overhead separated from the first fractionating tower.

It will further be understood that the proportions of any of the olefins to the corresponding paraffins (for example the proportion of butylene to butane) may vary considerably in accordance with the particular gases initially fed to the process and that such gases may comprise largely paraffinic constituents, this being largely a function of the type of cracking operation from which the gases have been initially derived. Thus, where the gases are largely paraffinic in character, the overhead from the tower 40 will comprise largely ethane, the overhead from the tower 15 will comprise largely propane and the liquid effluent from the bottom of the tower 75 will consist largely of butane. In general however, both paraffinic and olefinic constituents will be present, as both paraffinic and olefinic constituents are found at least to some extent in the gases resulting from all oil-cracking operations.

The process of our invention is adapted to be employed wherever it is desired to separate mixed hydrocarbon gases of the character indicated into a plurality of fractions, such for example as an ethane-ethylene fraction, a propane-propylene fraction and a butane-butylene fraction. These various fractions, being different in character, may then be advantageously subjected to different types of conversion operations, or may be subjected to conversion operations maintained under different optimum conditions according to the natures of the individual fractions treated. Thus, the ethane-ethylene fraction and the propane-propylene fraction may be utilized for the production of ethyl chloride and propyl chloride, respectively, whereas the butane-butylene fraction may be subjected to elevated temperature and pressure, with or without the assistance of suitable catalysts, in order to effect the conversion thereof to polymer gasoline.

Moreover, as has been indicated herein above, by reducing a number of steps in the fractionation operation, we may similarly reduce the number of fractions segregated. Thus, by conducting the operation in two stages, we may remove methane as overhead from the tower 35 and may then complete the fractionation in a second

tower, withdrawing as overhead therefrom a fraction comprising ethane, ethylene, propane and propylene.

It will be understood that our invention is not limited to the illustrative details set forth herein, but may variously be practiced and embodied within the scope of the claim hereinafter made.

What we claim is:

The process of recovering gases relatively free from low boiling paraffinic gaseous constituents such as ethane from hydrocarbon gases containing the same in addition to higher boiling normally gaseous constituents, which comprises introducing said gases in at least partly liquefied form into a fractionating column, supplying to the upper portion of said column a refluxing and scrubbing medium, removing from the upper por-

tion of said column a gaseous fraction relatively rich in said low-boiling paraffinic gaseous constituents, removing from the lower portion of said column a liquid fraction, introducing the liquid fraction withdrawn from the first column 5 into a second column and subjecting it to fractional distillation to recover a gaseous fraction relatively free from said low boiling paraffinic gaseous constituents and a relatively high boiling liquid fraction consisting of the higher boiling 10 constituents of said gases, and returning a portion of the more closely separated product from the second column to the upper portion of the first mentioned column to constitute the refluxing and scrubbing medium supplied thereto. 15
